UNITED STATES PATENT OFFICE.

GEORGE O. SEWARD, OF NIAGARA FALLS, NEW YORK, ASSIGNOR TO AMERICAN MAGNESIUM CORPORATION, OF NIAGARA FALLS, NEW YORK, A CORPORATION OF NEW YORK.

ELECTROLYTIC APPARATUS.

1,408,141.

Specification of Letters Patent. Patented Feb. 28, 1922.

Application filed October 11, 1917, Serial No. 196,026. Renewed May 3, 1921. Serial No. 466,531.

To all whom it may concern:

Be it known that I, GEORGE O. SEWARD, a citizen of the United States of America, residing in Niagara Falls, in the county of 5 Niagara, State of New York, have invented certain new and useful Improvements in Electrolytic Apparatus, of which the following is a specification.

This invention provides an electrolytic furnace adapted for electrolyzing a bath of molten salts, or compounds, for example, of haloid salts; and particularly salts of metals which are lighter than the molten bath, so that upon being electrodeposited, or 10 separated, the metal rises through the bath and floats upon the top of the electrolyte. The apparatus is designed especially for use in practicing a process for electrodepositing magnesium which is set forth in another application for patent which I have prepared and which is intended to be filed concurrently, or substantially so, with the present application, filed November 19, 1917, patented July 22, 1919, No. 1,310,450.

25 In a prior United States Patent No. 880,489, patented February 25, 1908 to Franz von Kugelgen and George O. Seward, there is described and claimed an electrolytic process of producing magnesium or alloys thereof, 30 according to which magnesium oxid is added to a molten bath containing magnesium fluorid and a fluorid of a metal or metals electropositive to magnesium. My present invention relates to apparatus adapted to 35 performing operations of the above general character.

Fig. 1 of the accompanying drawing is a transverse section of the preferred construction of an electrolytic furnace according to 40 the present invention.

Fig. 2 is a plan of the furnace on a smaller scale.

In the drawings, 1 represents a metallic vessel or container for the bath, which is 45 preferably an unlined, rectangular vessel of cast iron or other suitable metal, preferably supported upon blocks 2 in such manner as to afford a free circulation of air beneath the vessel in order to avoid overheating.

50 The bath solidifies to a greater or lesser extent around the walls and upon the bottom, as indicated at 3, a central portion or pool 4 remaining fluid under the operating conditions. 5 represents the cathode which may 55 consist of a heavy plate of cast iron or other

metal extending longitudinally of the vessel and projecting vertically through an aperture 6 in its bottom. The cathode may be provided with a water-cooled base 7. The temperature at the bottom of the vessel is 60 such that the solidified bath sets around the base of the cathode, rendering any material leakage at this point impossible. Cooling-coils 8 may be provided in order to render this closure positive under all 65 operating conditions. The upper edge of the cathode may be beveled as indicated in order to facilitate the upward flow and detachment of the molten magnesium.

9, 9 represent the anodes which may be of 70 carbon or graphite, illustrated in Fig. 1 as depending into the bath upon either side of the cathode, and out of vertical alinement therewith. Any desired or suitable number of anodes may be provided. 10 indicates 75 a layer of magnesium oxid or of magnesium carbonate floating upon the surface of the bath and serving not only to retain the heat but also as a primary source of raw material for the production of magnesium, the magnesium oxid either dissolving progressively in the bath and undergoing electrolysis therein, or uniting with fluorin liberated by the current and hence restoring the magnesium fluorid content of the bath. In case 80 magnesium carbonate is used it is eventually converted into magnesium oxid by calcination in situ. Either magnesium oxid or magnesium carbonate is effective to protect the anodes, which are otherwise subject to 85 strong attack at or near the surface of the bath.

Cooling-pipes 11 are indicated near the surface of the bath on either side of the cathode, above its upper edge. The purpose 95 of these is to chill and thereby to solidify a limited portion of the surface area of the bath as clearly indicated in Fig. 1, the crust thus formed shielding the floating metal from the atmosphere but being readily 100 broken through when the metal is to be collected.

The process to be practiced with this construction of electrolytic-cell or furnace is fully set forth in my companion application above referred to. Suffice it here to say that for the production of magnesium, the bath or electrolyte should be composed of suitable fluorids, such that the molten bath will have a sufficient specific gravity to cause 110

the produced magnesium to rise constantly to the surface. This bath is maintained molten by a suitable current, a temperature of 900° to 1000° C. being found suitable.

- 5 At the same time a sufficient flow of water is maintained through the cooling pipes and jacket 7 to insure an incrustation of congealed salt around these pipes and where the cathode passes through the bottom of 10 the tank. As the source of heat is between the electrodes, no difficulty is experienced in maintaining the layer 3 of incrusted salt as a lining for the tank itself. The layer 10 of magnesium oxid or carbonate is replenished from time to time. The bath of molten magnesium accumulates within the chamber formed by the incrustation surrounding the pipes 11, until it reaches sufficient volume to make it desirable to 20 move it, when the molten metal is ladled out, or otherwise removed. It is found in practice that this can be done without a material loss of magnesium by burning.

The anodes are best arranged so that they 25 may be individually fed downwardly into the electrolyte as they are oxidized and consumed. For this purpose, they are carried by rods 12, suitably connected to them and suitably fastened to bus-bar 13. The clamping and adjusting means are not shown, as such means are well known in the art.

The use of separately adjustable anodes depending into the electrolyte and surrounded thereby is practically necessary, so that 35 they can be fed down from time to time as required without interfering with the continuous operation of the furnace; whereas if the furnace were constructed with an anode lining, as set forth in U. S. Patent No. 40 864,928, this lining would eventually be eaten away where it contacts with the electrolyte, and particularly at the surface of the bath, and this after a time would require that the operation of the furnace be 45 discontinued while renewing this anode lining.

It will be obvious that the proportions and arrangement may be considerably varied according to circumstances, and within the 50 skill and judgment of those skilled in this art, without departing from the invention.

What I claim is:

1. An electrolytic apparatus for producing a metal lighter than the electrolyte, comprising a vessel for containing a molten fluorid bath, having its walls so remote from the electrodes as to maintain an insulating layer of congealed salt thereon, a cathode projecting upwardly through such layer 55 into the vessel, independently adjustable anodes depending into the vessel out of vertical alinement with the cathode, and means for cooling the upper portion of the bath, located to separate the portion above the 60 cathode from the portion surrounding the

anodes whereby to form, by a local solidification of the bath, an enclosure for receiving the molten light metal which rises from the cathode.

2. An electrolytic apparatus for producing a metal lighter than the electrolyte, comprising a vessel for containing a molten fluorid bath, having its walls so remote from the electrodes as to maintain an insulating layer of congealed salt thereon, a cathode 75 projecting upwardly through such layer into the central portion of the vessel, independently adjustable anodes depending into the vessel on opposite sides of the cathode and out of vertical alinement therewith, and means for cooling the upper portion of the bath, located to separate the portion above the cathode from the portion surrounding the anodes whereby to form, by a local solidification of the bath, an enclosure for receiving the molten light metal which rises from the cathode. 80

3. An electrolytic apparatus according to claim 1, the chamber above the cathode formed by such cooling means covered over 90 and adapted to receive the separated light metal, and the space overlying the electrolyte surrounding the anodes adapted to receive a layer of material floating on the electrolyte. 95

4. An electrolytic apparatus for producing a metal lighter than the electrolyte, comprising a vessel for containing a molten bath, having its walls so remote from the electrodes as to maintain an insulating layer 100 of congealed salt thereon, a cathode, anodes depending into the bath and out of vertical alinement with the cathode, and means for cooling the upper portion of the bath located to separate the portion above the cathode from the portion surrounding the anodes, whereby to form by a local solidification of the bath, an enclosure for receiving the molten light metal which rises from the cathode. 105

5. An electrolytic apparatus according to claim 4, the enclosure formed by such cooling means being covered over and adapted to receive the separated light metal, and the space overlying the electrolyte surrounding 110 the anodes adapted to receive a layer of material floating on the electrolyte.

6. An electrolytic apparatus for producing a metal lighter than the electrolyte, comprising a vessel for containing a molten bath and having on its walls a layer of congealed bath material, a cathode and an anode, and means for cooling a portion of the bath located between the said anode and cathode to provide an enclosure, the said enclosure being covered over with a layer of incrusted material. 115

7. An electrolytic apparatus for producing a metal lighter than the electrolyte, comprising a vessel for containing a molten 120

bath and having on its walls a layer of congealed bath material, a cathode, and an anode, and means for cooling a portion of the bath located between the said anode and 5 cathode to provide an enclosure, the said enclosure being covered over with a layer of incrusted material and the space overlying the electrolyte surrounding the anodes adapted to receive a layer of material floating 10 on the electrolyte.

8. An electrolytic apparatus for producing a metal lighter than the electrolyte, comprising a vessel for containing a molten bath and having on its side walls a layer of congealed bath material, means for cooling a portion 15 of the bath remote from said walls to provide a barrier of congealed bath material, and a covering of solid metalliferous

material overlying the molten bath and extending from the said barrier to the said 20 layer.

9. An electrolytic apparatus for producing a metal lighter than the electrolyte, comprising a vessel for containing a molten bath, an anode and a cathode area of bath, 25 cooling means interposed between the said areas to form a local solidification of the bath, the cathode area being covered over with incrusted material and adapted to receive the separated light metal and the 30 anode area adapted to receive a layer of material floating on the electrolyte.

In witness whereof, I have hereunto signed my name.

GEORGE O. SEWARD.
